(57) **CLAIM**

The ornamental design for an exhaust pipe, as shown and described.

DESCRIPTION

FIG. 1 is a front and top perspective view of an exhaust pipe, showing my new design;

FIG. 2 is a rear and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is an enlarged top plan view thereof; and,

FIG. 8 is an enlarged bottom plan view thereof.

The broken lines in the figures illustrate portions of the exhaust pipe that form no part of the claimed design.
